(57) **CLAIM**

The ornamental design for a multifunctional docking station for cleaning robot, as shown and described.

DESCRIPTION

The patent or application file contains at least one drawing executed in color. Copies of this patent or patent application publication with color drawing(s) will be provided by the Office upon request and payment of the necessary fee.

1.1 is a front view of a first multifunctional docking station for cleaning robot;

1.2 is a back view thereof;

1.3 is a left view thereof;

1.4 is a right view thereof;

1.5 is a top view thereof;

1.6 is a bottom view thereof;

1.7 to 1.9 are three perspective views thereof;

2.1 is a front view of a second multifunctional docking station for cleaning robot;

2.2 is a back view thereof;

2.3 is a left view thereof;

2.4 is a right view thereof;

2.5 is a top view thereof;

2.6 is a bottom view thereof; and

(Continued)

2.7 to **2.9** are three perspective views thereof.
 The portions of the design shown in the color yellow in the reproductions of the first and second multifunctional docking stations form no part of the claimed design.
